UNITED STATES PATENT OFFICE.

HENRI A. SÉVIGNÉ, OF BOSTON, MASSACHUSETTS.

DESIGN FOR A HOOK.

SPECIFICATION forming part of Design No. 29,981, dated January 10, 1899.

Application filed December 16, 1898. Serial No. 699,508. Term of patent 7 years.

To all whom it may concern:

Be it known that I, HENRI A. SÉVIGNÉ, of Boston, in the county of Suffolk and State of Massachusetts, have invented a certain new and original Design for Hooks, of which the following is a specification.

This invention relates to a new and original design for a hook; and it consists of the novel features of shape and configuration hereinabove fully described and claimed and illustrated upon the accompanying sheet of drawings.

Of the said drawings, Figure 1 represents in perspective view a hook embodying my design. Fig. 2 represents a front elevation of the same.

The article of manufacture embodying my design is shown as consisting of a plate *a*,

substantially diamond-shaped. Two bars or posts *b b* extend from the ends of said plate and meet at a point in front of the center thereof. From the meeting-point of said posts two arms *c c* project outward, so that the arms *b b* and *c c* present the appearance of a cross in front elevation. In side elevation the hook presents the appearance of an isosceles triangle.

I claim—

The design for a hook, substantially as shown and described.

In testimony whereof I have affixed my signature in presence of two witnesses.

HENRI A. SÉVIGNÉ.

Witnesses:

MARCUS B. MAV,
C. C. STECHER.
